CAR CONSTRUCTION

David Hindahl, Chicago, Ill., assignor to Rodger Ballast Car Company, Chicago, Ill., a corporation of Maine

Application September 3, 1938, Serial No. 228,342

6 Claims. (Cl. 105—251)

This invention relates to improvements in dump cars of the type known as ballast cars, from which the lading may be discharged either centrally between the rails of the track, or to the outside of the rails, or to both positions at the same time, and which are commonly known as selective ballast cars. A car of this type is shown in its general features in the patent to Morey No. 1,694,077 of December 4, 1928.

It is the general object of this invention to provide a car of this type in which the assembly at the shop is greatly facilitated, the number of operations in manufacture reduced, its weight materially lessened, resulting in a reduction in the cost of manufacture while at the same time preserving the required strength of the various structural parts.

The various features cooperating to produce this result are an improved construction of certain parts of the hopper parts, enabling the use in this car of a pre-fabricated side wall having inside stakes which extend continuously from the top chord to the bottom chord of the side wall and which may be applied to the other parts of the car as a unit during the assembly operations.

To provide further a novel means for bracing and supporting the side walls and other component parts of the car, eliminating the ordinary gusset plates hitherto used.

To provide further a unitary bracket casting for supporting the longitudinal shaft of the operating mechanism, which casting is provided with lubricating means for the shaft while at the same time bracing and supporting the inner side slopes of the hopper.

These and other objects not specifically enumerated will readily appear to one skilled in the art as the following description proceeds, it being understood that the particular embodiment of the invention herein disclosed is merely given by way of illustration and is not to be considered as limiting the invention in any respect as the scope thereof may be determined from the appended claims when given the broadest possible interpretation permitted by the prior art.

Referring to the drawings—

Figure 1 is a side elevational view of the car of this invention, in its partially assembled state; that is to say, with its side wall not yet applied;

Figure 2 is an elevational view of the preformed side wall to be applied to the car of Figure 1;

Figure 3 is a fragmentary perspective view of a car constructed in accordance with this invention, showing the arrangement of parts as seen from the inside;

Figure 4 is a cross-sectional view taken through the body of the car shown in Figure 1, and illustrating the construction of the hoppers, side walls and hopper doors;

Figure 5 is an enlarged perspective of a novel form of bracket, which constitutes a part of this invention, and which is utilized as a support for slope sheets of the hoppers, a center sill separator, as well as means for mounting the center shaft of the door operating mechanism, with lubricating means therefor.

By referring to the drawings, it will be noted that this invention is here illustrated as embodied in a car having the usual wheels 10, which support the usual trucks (not shown) under each end of the car, each of which has the usual truck bolster. Supported on the truck bolsters is a center sill 12 which extends from one end of the car to the other, and adjacent each end is a body bolster 13 which serves as a cross-member for supporting each end of the car. The construction of these bolsters is more clearly shown in Figure 1, from which it will be noted that the bottom portion thereof comprises a strap 14 which underlies the lower edge of the body bolster and passes downwardly under the center sill and upwardly on the other side in such manner as to connect the bottom chords of the side walls.

On top of the body bolster 13 are end slope sheets 15 which are preferably made of sheet metal and which are disposed at the proper angle to cause the lading to slide downwardly toward the discharge doors under the action of gravity. The slope sheets are preferably formed with upstanding side flanges 16 which are subsequently riveted to the side walls in the manner hereinafter explained.

At the lower central portion of the slope sheets 15 where they intersect the surface of the center sill, the slope sheets are cut away so as to straddle the center sill and its hood. This hood of inverted V-shape extends continuously over the center sill from end slope to end slope. At the edge of the cut-away portion the center sill hood terminates in a flange 15' which underlies the edge of the cut-away portion of the end slope sheets so as to support the same and to close any crack that might otherwise be left there. The cut-away portions lie adjacent the side faces of the said center sill 12 and are anchored to angle brackets 17 which are riveted to the faces of the center sill and which have an upper flange in engagement with the edge formed by the cut-out in the end slope sheet. This bracket not only supports the edge of the slope sheet but also closes

any crack that would otherwise be formed along the side face of the center sill.

The side slope sheets 20 are continuous from end slope to end slope adjacent the hoppers, so 5 as to form side shedding surfaces directing the lading toward the discharge doors.

One particular feature of novelty in this invention resides in the construction of these side slope sheets, and more especially in the notches 10 21 along the upper edge thereof, which are most clearly shown in Figures 1 and 3. These notches are so formed and located as to receive the side stakes of the car in a manner hereinafter more fully set forth.

15 It is important to observe here, however, that these notches make possible the use of pre-fabricated unitary wall constructions having the side stakes on the inner surface of the wall extending uninterruptedly from the upper chord to 20 the lower chord.

The side slope sheets have inclined edges at their ends, as clearly shown in the drawings, which conform to the incline of the end slope sheets, so 25 that the flanges 22 which extend inwardly from the inclined edges of the side slope sheets may engage the lower edges of the end slope sheets to form by rivets or other suitable means, an attachment between the cooperating edges of the side and end slope sheets, respectively. Inasmuch as the side slope sheets are inclined inwardly from top to bottom, the end slope sheets are preferably cut at an angle along their lower outside edges to conform to the angularity of the side slope sheets. This construction permits a 30 neat and strong joint between the edges of the slope sheets.

At the bottom edges, disposed on opposite sides of the center sills, a depending apron 23 is provided, held by suitable braces 24, all in a manner 40 which is clearly understood in this art. These aprons are clearly shown in Figures 1 and 3, and provide means for confining the lading during the discharge operation to a path of flow determined by the opening of the doors and preventing the 45 lading from spilling over the edges of the discharge doors. The side slope sheets preferably extend continuously throughout the entire length of the hopper portion of the car, and at a central point in their length are strengthened and supported by a central cross-tie 25, clearly shown in 50 Figures 1, 3 and 4. As shown in Figures 3 and 4, this cross-tie is of sufficient length to extend from one of the side slope sheets to the other so as to be secured thereto by connection with the flanges 55 26 of angular members 27, which are in turn secured to the side slope sheets.

The central portion of the cross-tie 25 is cut away to form an opening 28 which conforms in shape to the upper surface of the center sill hood 29.

At the location of the central cross-tie 25, there is an angle member 30 which conforms to the shape of the hood. This angle has a web 30' disposed against the side of the cross-tie and secured thereto by rivets or other suitable means. It is also secured to the lower end of the diagonal braces 32, as hereinafter described. A flange 30'' abuts the upper surfaces of the center sill hood and the face of the center sill. This flange 30'' is riveted through the center sill to the portion 12 70 of one of the brackets 70 located at this point, hereinafter described. The lower ends of the flanges 30' of the member 30 thus provide securing means for the diagonally disposed braces, 75 while the flange 30'', secured as described through

the center sill to the portion 12 of the bracket 70, enables this bracket 70 to receive and transmit the thrusts and strains imposed upon the diagonal braces. The braces 32 are also suitably secured to the cross-tie 25.

As further illustrated in Figure 3, it is apparent that the internal braces 32 may be of channel construction and extend upwardly to a point adjacent the top of the side wall so as to present a portion in contact with the inwardly extending flange of the side stake. These contacting parts may be riveted or otherwise secured, as shown at 50 in Figure 3.

One feature of this construction is that a bent strap member 51 is adapted to overlie the upper chord and the upper end of the diagonal brace 32, with the horizontal portion 52 thereof riveted to the horizontal flange of the upper chord and the downwardly extending portion 53 thereof secured to one of the flanges of the channel 20 brace 32.

These diagonal braces take the place of the usual heavy gusset plates which are connected ordinarily to the center tie and to a side stake of the car, the rivets at the side stake being largely 25 in tension and the gusset plates being of considerable weight owing to the amount of material used therein. By the use of the diagonal braces attached by rivets to the top chord, I place the rivets in shear, thus giving the necessary 30 strength at this point. Without the use of a large number of rivets, I am enabled to provide the necessary support for the sides by the use of less material, and owing to the connection of these braces to the center sill and cross-tie, to 35 form a firm and rigid structure.

The car of this invention involves the use of unitary preformed side wall constructions of substantially the type illustrated in Figure 2, each of which comprises an upper chord 35 and a lower 40 chord 36. As shown in Figure 3, these chords are preferably of angular construction of the type now in common use. Connecting the upper and lower chords are vertically disposed side stakes 37 which, in combination with certain other elements, constitute an essential feature of this invention. The side stakes are preferably disposed in the manner shown, that is to say, with the endmost stake spaced inwardly from the extreme 45 ends of the upper and lower chord members and placed at the bolster ends.

The space formed between the end side stakes is covered with a large side sheet 38, which may be formed in any suitable manner, but as here 55 illustrated is preferably formed as a single sheet of steel, secured by rivets or other suitable means to the side stakes and to the top and bottom chords. At the ends of the side walls of the car are smaller side plates 39, which are preferably formed with an angular bottom edge spaced 60 upwardly from the bottom chord substantially in the manner shown. It is apparent that it is not necessary to have the side sheet at this portion of the car extend all the way to the bottom chord because it is only necessary to enclose the hopper portion thereof. These sheets 39 are 65 likewise secured by rivets or other securing means to the upper chord and to the end side stakes against which they are positioned. This assembly is made before application of the side to 70 the car.

In assembling the car of this invention, the center sill, with its hood 29, cross-tie 25 and the body bolsters 13 already attached, is first placed in the proper manner on the car trucks, or any 75

other suitable supporting means which will enable it later to be mounted on the car trucks. Thereafter the end slope sheets 15 are mounted in place and supported on the angular flange 31, as shown in Figure 1 of the drawings, at the upper end of the body bolsters. The lower end of the end slope sheets are disposed so as to straddle the center sill and the edges of the cut-out are secured to the flanges 15' provided at the end of the center sill hood.

Next the side slope sheets are mounted in position and their ends attached to the inclined side edges of the end slope sheets and their central portions supported by attachment to the central cross-tie 25. The central cross-tie, which is cut out in its center to overlie the center sill hood, is anchored to the hood and center sill by means of rivets or otherwise secured through the flanged member 30.

At this point in the assembling operation, the car is ready to receive as a unit the preformed unitary side wall constructions, and it will be noted that the top edges of the side slope sheets have been notched to receive the side stakes located on the inner surface of the side walls.

Next the entire wall assembly as a preformed unit, constructed in substantially the manner illustrated in Figure 2, is moved into position against the side of the car, with the vertically disposed side stakes extending upwardly through the notches 21 at the upper edge of the slope sheets. The flanges of the lower chord members are next inserted between the bottom strap member 14 and the lower edges of the vertical web and their attaching angle members which constitute the body bolsters. The straps 14 are spaced slightly downwardly from the edges and flanges thereabove so as to provide a receiving opening for the inwardly projecting flanges of the lower chords. The parts thus assembled are held by suitable rivets or otherwise suitably secured. This space for lower chord flanges is shown at 40' in Figure 1.

The side sheet is further secured by rivets to the vertically disposed flanges 16 of the end slope sheets and to the upstanding flanges 40 at the upper edge of the side slope sheets. After both side sheets have been moved into position and secured as above described, the vertically disposed corner posts 45 are applied and held in position by a connection between the upper and lower chords of the side wall. The members 45 have secured therebetween an end plate 46 which closes the upper end of the car and which is preferably joined by rivets or other suitable means to an upper flange 47 of the end slope sheet. The upper edge of the plate 46 is preferably secured to an end top chord 48.

It will be noted from Figure 3 that the side slope sheets 20 are reinforced with angle braces 27 adjacent the central side stakes, whereby the slope sheets 20 may be secured to the side stakes by rivets or other suitable means as shown in Figure 3. These braces 27 also serve to connect the side slope sheets to the cross-tie 25 through the flanges 26.

It is apparent from this description that the applicant has provided a new and improved car construction which differs from the constructions heretofore employed, in that the side stakes are disposed on the inner surface of the car wall and extend uninterruptedly from the top chord to a bottom chord, which chord is disposed below the upper edge of the side slope sheets, and that the

upper edge of the side slope sheets are notched to accommodate the side stakes.

It will be noted that the side stake is provided with a slight depression, as at 54, adjacent the top, to accommodate the top chord and yet leave a flush surface on the outside for the side sheet 38. Similarly at the bottom, the side stake is slightly recessed, as at 55, to accommodate the vertical flange of the lower chord 36 and for providing a flush outer surface for the side sheet 38.

The bottom edges of the side slope sheets are preferably reinforced by a Z-bar 60 in substantially the manner now common in the art. Also, at spaced points throughout the length of the car, brackets 65 are provided, secured in a suitable manner between the horizontal flange of the lower chord at their outer edges and the bottom edges of the side slope sheets at their inner edges. These brackets form suitable supports for door hinges from which the door may be suitably hung for the opening and closing movement.

Adjacent the lower edges of the center sill are one or more brackets 70 of the type illustrated in Figure 5, which comprise the central triangular part 70' and the side wing members 71. The upper portion of this bracket 70 has parallel vertically disposed faces 72 which are attached to engage the inner surfaces of the center sill. This arrangement is clearly shown in Figure 4. The central triangular part 70' is formed, as shown, in a trough shape adapted to receive packing for lubricant and to support the crank member of the operating mechanism.

The disposition of the bracket causes the flat faces 73 of the side wings 71 to underlie the horizontal flanges of the center sill so that these parts may be suitably secured for anchoring the bracket. When the bracket is thus mounted, the side wings 71 with their inclined outer surfaces 75 are so disposed as properly to support slope sheets 76 on opposite sides of the center sill. The parts 75 are notched at 75', as shown, to underlie corresponding notches 96 on the slope sheets 76. The bracket 70 at the middle portion of the car is connected as before described, through the angle member surrounding the hood and center sill to the lower end of the braces 32, transmitting the strains imposed on these braces and acting also as a separator for the center sill. The slope sheets 76 complete the hopper opening so that a rectangular opening is defined between the slope sheets 76, side slope sheets 20 and the end hopper aprons 23.

Carried on the brackets 65 and disposed so as to control the hopper openings, are doors of any suitable construction not here shown or described.

From the above description it will be apparent that the applicant has provided a new and improved car construction which embodies many novel features, particularly in that the side walls may be prefabricated with their side stakes on the inner surfaces, which extend uninterruptedly from the top chord to the bottom chord in a construction which has side slope sheets which are notched to receive the side stakes.

In addition to the foregoing, various other novel features will be apparent to one skilled in the art, all of which is specifically set forth in the appended claims.

I claim:

1. A dump car construction comprising in combination a center sill, end slope sheets supported on said center sill, side slope sheets extending downwardly and inwardly a substantial

- distance from the plane of the associated side walls of said car and connected between said end slope sheets and having notches along the upper edges thereof which are open exteriorly 5 and are adapted to receive side wall side stakes by lateral movement of said side stakes thereinto, and side walls having upper and lower chords and inside side stakes and connected to said end and side slope sheets respectively, with the side stakes thereof disposed in said notches and with the lower chord thereof disposed a substantial distance below the upper edge of said side slope sheets.
2. A car of the character described comprising in combination a center sill, end slope sheets supported on said center sill, side slope sheets connected at their ends to said end slope sheets and having notches along their upper edges, said notches being exteriorly open and adapted 10 to receive side wall side stakes by lateral movement of said side stakes thereinto and prefabricated side walls comprising upper and lower chords, inside side stakes and side sheets and secured to said side and end slope sheets with the side stakes thereof disposed in said notches and with said side slope sheets extending downwardly and inwardly from a point substantially above the lower chord to a point substantially inwardly from the plane of the associated side walls of said car.
3. A car of the character described comprising in combination a center sill, end slope sheets, side slope sheets connected at their ends to said end slope sheets and having notches along their upper edges, said notches being exteriorly open and adapted to receive side wall side stakes by lateral movement of said side stakes thereinto, prefabricated side walls comprising upper and lower chords, inside side stakes and side sheets and secured to said side and end slope sheets with the side stakes thereof disposed in said notches, and with said side slope sheets extending downwardly and inwardly from a point substantially above the lower chord to a point substantially inwardly from the plane of the associated side walls of said car, and a cross-beam connecting the center sill and said side slope sheets.
4. A car of the character described comprising in combination a center sill, end slope sheets, 50 side slope sheets connected at their ends to said end slope sheets and having notches along their upper edges, said notches being exteriorly open and adapted to receive side wall side stakes by lateral movement of said side stakes thereinto, prefabricated side walls comprising upper and lower chords, inside side stakes and side sheets and secured to said side and end slope sheets with the side stakes thereof disposed in said notches, and with said side slope sheets extending downwardly and inwardly from a point substantially above the lower chord to a point substantially inwardly from the plane of the associated side walls of said car, a cross-beam connecting the center sill and said side slope sheets, and inclined braces disposed centrally of said car extending from said cross-beam at the location of the center sill and the upper chords of said side walls respectively.
5. A car comprising a center sill, end slope sheets supported on said center sill, side walls, and side slope sheets extending downwardly and inwardly a substantial distance from the plane of the associated side walls of said car, said side walls comprising upper and lower chords, side stakes and side sheets disposed outside of said side stakes, the upper edges of said side slope sheets being a substantial distance above said bottom chords and having notches therein accommodating said side stakes and being exteriorly open and adapted to receive said side stakes by lateral movement of said side stakes into said notches.
6. A car comprising a center sill, end slope sheets supported on said center sill, side walls, and side slope sheets extending downwardly and inwardly a substantial distance from the plane of the associated side walls of said car, said side walls comprising upper and lower chords, side stakes and side sheets disposed outside of said side stakes, the upper edges of said side slope sheets being above said bottom chords and having notches therein accommodating said side stakes and being exteriorly open and adapted to receive said side stakes by lateral movement of said side stakes into said notches, the upper edges of said side slope sheets being fastened to said side sheets between the upper and lower chords thereof.

DAVID HINDAHL 50

CERTIFICATE OF CORRECTION.

Patent No. 2,167,362.

July 25, 1939.

DAVID HINDAHL.

It is hereby certified that error appears in the printed specification of the above numbered patent requiring correction as follows: Page 2, second column, line 13, and page 3, first column, line 64, for "Figure 3" read Figure 4; and that the said Letters Patent should be read with this correction therein that the same may conform to the record of the case in the Patent Office.

Signed and sealed this 12th day of September, A.D. 1939.

Henry Van Arsdale,
Acting Commissioner of Patents.
